UNITED STATES PATENT OFFICE.

LAURENCE S. LACHMAN, OF NEW YORK, N. Y.

SASH OR FRAME CONSTRUCTION.

1,100,247.

Specification of Letters Patent. Patented June 16, 1914.

Application filed September 26, 1913. Serial No. 791,945.

To all whom it may concern:

Be it known that I, LAURENCE S. LACHMAN, a citizen of the United States, and a resident of New York, in the county of New York and State of New York, have invented certain new and useful Improvements in Sash or Frame Construction, of which the following is a specification.

My invention relates to window sash or frame construction and particularly to the manner of securing and locking the intersecting members together as well as to the construction of the joint itself.

The invention is particularly adapted for and useful in constructing metal window sashes and frames but it will be understood that its application is not limited to this use as the utility is of wide scope and applicable to any suitable metal manufactures.

The object of the invention is to provide a simple, cheap and efficient means for locking intersecting members to each other.

In the accompanying drawings, Figure 1 is a plan view of intersecting members prepared for securing together in accordance with this invention. Fig. 2 illustrates the parts of a frame prepared in accordance with this invention and arranged one above the other in the relation in which they are assembled, parts being shown in cross-section. Fig. 3 is a cross-section through the finished joint. Fig. 4 is a plan view of the finished joint. Fig. 5 is a plan view of one of the frame members illustrated in Fig. 1. Fig. 6 is a plan view of a modification in the form of opening made to expose the webs of the intersecting members.

In the drawings 1 and 2 indicate metallic intersecting members of a structure which may be a window sash, frame or other similar device.

The members 1 and 2 each consist of a strip of metal having a web portion 3 and a flange or flanges 4 projecting therefrom and are preferably made of standard shaped parts owing to the cheapness of them over specially formed members and the facility with which they can be obtained. Preferably the said members are T-shaped in cross-section as such shape is especially applicable for use in construction of window sashes or frames, the angle between the web and each flange forming a pocket for the reception of

the window pane and the putty or other securing material.

Each of the members 1 and 2 at the point or points of desired intersection is cut away so as to expose the upper edge of the web. According to one method of carrying the invention into effect, the flanges 4 are cut away or removed by a stamping operation from each side of the web 3 as indicated in Fig. 5, in this case the opening having an arc shaped edge 5 and a miter 6. The specific form taken by the cut out portion of the flange 4 is immaterial to this invention, another form of opening being illustrated in Fig. 6 in which the flanges are cut away at right angles to the web and of a width equal to the width of the flange 4.

The parts may be removed, if desired, by a simple stamping operation and as the flanges on both the members 1 and 2 are cut away alike but one set of dies are necessary.

The webs of the members 1 and 2 are also each slotted in a place in line with the center of the removed parts of the flanges 4. For instance, the web 3 of the member 1 is provided with a slot 7 entering from the lower edge of the web and of a width equal to the thickness of the web while the web 3 of the member 2 is provided with a similar slot 8 entering from the top edge of the web, the slots 7 and 8 being of sufficient depth that when the members 1 and 2 are placed crossing each other with the slots in line they can be intermeshed until the flanges 4 of each member lie in the same plane. When so placed the miters 6 of each member engage and the members appear as shown in Fig. 1.

9 indicates a metallic button or connector of any desired design and provided with welding projections depending from its under surface preferably in the form of a circular ridge 10. The button or connector may also be provided, if desired, with a central depending pointed lug or pin 11, the point of which enters a prick punch hole 12 in the web 3 (Fig. 1) and serves to centrally locate the button 9 when said button is placed by hand.

The button 9 is placed over the cut away portions of the flanges and centrally of the intersecting webs 3, the ridge 10 of the button intersecting the edges of the webs at

four points about the intersection. These intersecting points of ridge and webs form isolated points of contact which allow the parts to be readily and quickly joined by the electric welding process.

By welding the parts together, a perfect, strong bond between the sash or frame members as well as simplicity and beauty of finish is attained.

10. To electrically weld the button 9 to the members 1 and 2, the parts are held between the electrodes of a suitable electric welding machine and current is passed from one electrode to the other through the work at 15 the same time pressure being applied, preferably through the electrodes, to force the parts together and complete the weld. As the electric current passes from the members 1 and 2 to the button 9, the points of isolated 20 contact formed by the intersections of the ridge 10 and exposed edges of the webs 3 soften and by the application of the pressure coalesce with each other and form four points of welded union around the intersecting webs. The electric welding process being now so well understood and so universally practised, it is thought that any further specific description of its use in this invention is unnecessary.
30. It will be understood that the type of intersecting members herein set forth is for the purpose of illustration only and that various modifications and equivalents of the parts herein shown might be resorted to without departing from the spirit of the invention.

What I claim as my invention is:—

1. The method of making a sash or frame joint consisting in providing flanged strips, cutting away the flanges of said strips at the 40 point of intersection to expose the web, placing a button over such intersecting webs and welding said button thereto.
2. The method of making a sash or frame joint comprising intersecting flanged strips, 45 consisting in cutting away the flange of said strips to expose the webs at the intersection and electrically welding a button to said webs.

3. The method of making a sash or frame joint comprising intersecting flanged strips, 50 consisting in cutting away the flange of said strips to expose the webs at the intersection, superimposing a button having welding projections placed in contact with said exposed webs and electrically welding said button to 55 said webs by said projections.

4. The method of making a sash or frame joint comprising intersecting flanged strips, consisting in cutting away the flange of said strips to expose the webs at the intersection, 60 superimposing a ridged button over said intersection with the ridge in contact with said webs and electrically welding said button thereto by said ridges.

5. A sash or frame joint comprising 65 flanged strips intersecting each other with the flanges in the same plane, said flanges being cut away at the intersection and the webs exposed and a button welded to said webs and concealing the openings in the 70 flange.

6. A sash or frame joint comprising flanged strips intersecting each other with the flanges in the same plane, said flanges 75 cut away at the intersection whereby the intersecting webs of said strips are exposed and a button spanning said intersection and welded to said webs at each side of the intersection.

7. A window sash or frame comprising T- 80 shaped intersecting members arranged with the flanges of said members in the same plane, the flanges of each member being cut away and the intersecting edges of the web exposed adjacent thereto and a ridged button 85 superimposed over said exposed webs and welded thereto by said ridge.

Signed at New York, in the county of New York and State of New York this 25th day of September, A. D. 1913.

LAURENCE S. LACHMAN.
